US00D985763S

(12) **United States Design Patent** (10) Patent No.: **US D985,763 S**
Miller et al. (45) Date of Patent: ** May 9, 2023

(54) **MEDICAL FACE MASK**

(71) Applicant: **Intersurgical AG**, Vaduz (LI)

(72) Inventors: **Andrew Neil Miller**, Wokingham (GB);
Matthew James William Leary,
Wokingham (GB); **Simon Robert Payne**, Wokingham (GB); **David Simon Bottom**, Wokingham (GB)

(73) Assignee: **INTERSURGICAL AG**, Vaduz (LI)

(**) Term: **15 Years**

(21) Appl. No.: **35/513,656**

(22) Filed: **Aug. 12, 2021**

(80) **Hague Agreement Data**

Int. Filing Date: **Aug. 12, 2021**

Int. Reg. No.: **DM/216285**

Int. Reg. Date: **Aug. 12, 2021**

Int. Reg. Pub. Date: **Feb. 18, 2022**

(51) **LOC (14) Cl.** **29-02**

(52) **U.S. Cl.**

USPC **D24/110.1**

(58) **Field of Classification Search**

USPC D24/110.1, 110.2, 110.4, 209; D29/108;
D3/269

CPC B63C 11/16; A62B 23/025; A61M 16/06;
A61M 16/085; A61M 16/0616
